UNITED STATES PATENT OFFICE.

BRITTON HYBARGER, OF TANGIER, INDIANA.

SIGNAL DEVICE.

Application filed February 25, 1927. Serial No. 170,897.

This invention has for its object the provision of an automatic signal device for railroad crossings, so that the oncoming train will itself signal motorists and pedestrians 5 of its approach.

In the drawings:

Figure 1 shows a perspective view of the device in operation,

Figure 2 shows a side elevation of the device,

Figure 3 shows a cross section taken on the line 3—3 of Fig. 2.

Referring to Fig. 1, 1 indicates a roadway, 2—2, a railroad track crossing same, 3—3 a pair of posts mounted one on each side of the roadway and containing within themselves signal arms 4 and the lever means adapted to raise the arms into warning position. One of these posts is also indicated 20 in Fig. 2 by numeral 3, and shows the arm in extended or signalling position. A hand 4^a is carried on the end of the arm. A human face is preferably painted on the post so as to give the whole the resemblance of a 25 human being with an arm extended.

The means by which the arm is extended and retracted by the train are as follows: 5 is a short lever, carried on trunnions and fastened to a base by same, said base being fastened to the ties of the track and located at a considerable distance along the track from the crossing.

The lever 5 has the general shape of a diamond except that the corners are rounded and the edges slightly bulged, providing a curved cam surface. When no train is passing this lever or cam is in upright position midway between the rails. The lower end of the lever 5 weighted, has fastened to it, 40 by any suitable means the end of a cable 6, which extends between the rails of the track almost to the crossing, that is, to where a rocking member 7 is located. This rocking member consists of a base located between 45 the ties, and below the rails a shaft 8 carried by the base and extending into the post 3. The shaft is rotatably mounted in the bearings of the base. The shaft extends preferably all the way across the distance 50 between the rails. Midway between the rails, a pair of levers are attached at right angles to the shaft and at somewhat less than a right angle to each other. Both are attached to the shaft at its middle point.

One of the levers is short, that is, it does not project above the rails at any time while the other one is long enough to project far enough above the rails to engage the cowcatcher of a locomotive. The longer lever is nearer the crossing.

Within the post the shaft 8 is connected to a lever arm 9 (Fig. 2) extending at right angles to same, which is in turn hinged to a link member 10, which is hinged to the warning arm 4, which is trunnioned near its inner or shoulder end to the post.

The operation of the device is as follows: The cowcatcher of the locomotive first strikes the lever 5 and pushes it forward, thereby exerting a pull on cable 6 and short lever of rocker 7, thereby turning shaft 8 and pulling down associated lever 9 from within the post and pulling short end of arm 4 by means of link 10, thereby raising arm. As the train advances, the cowcatcher engages the longer lever of rocker 7 pushing shaft 8 in the opposite direction from the operation just described and sets in motion the same operation of levers, but in reverse direction. By making the cable 6 longer than any train operating over the road, simultaneous operation of the two levers will never occur. By providing one of these devices on each side of a crossing complete protection is assured. The two devices should be oppositely arranged.

I claim:

In combination with a railway crossing, a post, a warning arm therein, a link and lever also contained therein for extending and retracting said arm, a rocker shaft extending across the track below the rails, a bell crank lever fixed to said rocker shaft and having long and short arms, a cable fast to the short arm of the bell crank lever, a lever at a substantial distance away from the crossing, fulcrumed in its middle, and connected to the cable and normally disposed in a vertical position to be engaged by moving railway trains whereby to place the cable under tension to rock the bell crank lever to a position to dispose its long arm in a vertical position and to actuate the rocker shaft to extend the warning arm, the long arm of the bell crank lever being subsequently engaged by the train to reversely actuate the mechanism to retract the warning arm.

BRITTON HYBARGER.
